US00D697028S

(12) **United States Design Patent**
Workman et al.

(10) **Patent No.:** **US D697,028 S**
(45) **Date of Patent:** **** Jan. 7, 2014**

(54) **ENERGY STORAGE AND POWER SUPPLY DEVICE**

(75) Inventors: **Robert E. Workman**, Morgan, UT (US); **Erik R. Workman**, Salt Lake City, UT (US); **Norm Krantz**, Logan, UT (US); **Joseph R. Atkin**, Highland, UT (US); **Walker Ford**, Bluffdale, UT (US)

(73) Assignee: **Goal Zero LLC**, Bluffdale, UT (US)

(**) Term: **14 Years**

(21) Appl. No.: **29/410,376**

(22) Filed: **Jan. 6, 2012**

(51) LOC (10) Cl. **13-02**

(52) U.S. Cl.

USPC **D13/110**

(58) **Field of Classification Search**

USPC D13/107, 108, 110, 137.1, 137.2, 138.1, D13/138.2, 138.3, 138.4, 139.1–139.8, 146, D13/147, 152, 154, 155, 156, 158, 169, 170, D13/173, 177; D14/432, 433; 174/50, 52, 174/53, 54, 55, 56, 58, 59, 66, 480, 481, 174/494, 505; 439/105–107, 344, 378, 535, 439/650–655, 675, 676, 692, 693, 709

(57) **CLAIM**

We claim the ornamental design for a energy storage and power supply device, as shown and described.

DESCRIPTION

FIG. 1 is a front perspective view of an energy storage and power supply device showing the claimed design;

FIG. 2 is a left side view thereof; and,

FIG. 3 is a right side view thereof.

The broken line showing of FIGS. 1-3 represents unclaimed subject matter and forms no part of the claimed design.

1 Claim, 1 Drawing Sheet
